S. L. SELLARS.

CLEANING DEVICE.

APPLICATION FILED APR. 14, 1920.

Patented June 20, 1922.

Sidney L. SELLARS, *INVENTOR.*
By *Hicks, Henklein, Farnham & Co.* *ATTORNEYS.*

UNITED STATES PATENT OFFICE.

SIDNEY L. SELLARS, OF PHILADELPHIA, PENNSYLVANIA.

CLEANING DEVICE.

1,419,948.

Specification of Letters Patent. Patented June 20, 1922.

Application filed April 14, 1920. Serial No. 373,684.

To all whom it may concern:

Be it known that I, SIDNEY L. SELLARS, a citizen of the United States, residing in the city and county of Philadelphia, State 5 of Pennsylvania, have invented a new and useful Cleaning Device, of which the following is a specification.

My invention relates to a novel construction and arrangement of a cleaning device 10 which is designed to utilize compressed air, water, or a cleaning fluid, or any combination of air, water and cleaning fluid, the cleaning fluid being automatically drawn into the device by the vacuum created by the 15 compressed air.

Although not limited to use in the cleaning of vehicles of the motor driven or other types, it is especially adapted for such purposes and it has been found in practice that 20 one man in the same time can clean as many automobiles as five men can do working by hand in the usual manner.

With the above and other objects in view, my invention consists of a novel cleaning 25 device adapted to employ alone or in combination water, compressed air, and a cleaning fluid.

Other novel features of construction and 30 advantage will hereinafter more clearly appear in the detailed description of the invention.

For the purpose of illustrating my invention, I have shown in the accompanying drawing a typical embodiment thereof which 35 is at present preferred by me, since said embodiment will give in practice satisfactory and reliable results. It is, however, to be understood that the various instrumentalities of which my invention consists can be 40 variously arranged and organized and that my invention is not limited to the precise arrangement and organization of these instrumentalities as herein shown and described.

Figure 1 represents, in side elevation, a 45 cleaning device, embodying my invention.

Figure 2 represents a top plan view of my device.

Figure 3 represents a section on line 3—3 50 of Figure 1.

Figure 4 represents, in side elevation, one of the clamping devices employed.

Similar numerals of reference indicate 55 corresponding parts.

Referring to the drawings.

1 designates a pipe forming the discharge

end or nozzle of a cleaning device embodying my invention. The pipe 2 is provided with a manually controlled valve 3 and discharges into the pipe 1, and at its rear end 60 is adapted to receive a flexible hose 4, while its opposite end is connected to the pipe 1 by means of a union or fitting 5 to which is connected a manually controlled valve 6. The valve 6 has connected to it a flexible 65 hose 7 which forms a vacuum pipe. 8 designates a compressed air pipe which is connected to and spaced from the pipes 1 and 2 by means of the spring clips 9, the free ends of which are deflected to form rounded 70 portions which closely engage their respective pipes. As the compressed air pipe 8 is smaller than the other pipes, the hook formed by the bent ends of a clip is smaller at one end than it is at its other end. The 75 pipe 8 is provided with a manually actuated valve and the rear end of such pipe is adapted to receive a flexible hose 11 which leads from a source of fluid supply, such as, for example, an air compressor. The pipe 8 at 80 its forward portion is bent towards the pipe 1 and has a tight fit in an aperture 12. From the aperture 12 the pipe 8 telescopes within the pipe 1 for a desired distance, as indicated at 13, so that a passage 14 is formed 85 between the pipes 1 and 8. The different lines of hose 4, 7 and 11 are preferably tied together by means of a cord 15.

The operation of my novel cleaning device will now be readily apparent to those 90 skilled in the art to which this invention appertains, and is as follows:—

The operator grasps the cleaning device by means of the different pipes which form handles in order to facilitate the manipulation of the cleaning device. If the operator desires simply to use water the valves 6 and 10 are closed and the valve 3 opened. If a combination of water and compressed air is desired the valves 3 and 10 are opened and 100 the valve 6 is closed. If a cleaning fluid is to be employed, such as, a soapy mixture or gasoline, the vacuum pipe 7 is placed in communication with such cleaning fluid and the valve 6 opened and one or both of the 105 valves 3 and 10 opened, whereupon a vacuum will be created in the vacuum pipe 7 and the cleaning fluid will be drawn into the nozzle 1 and discharged from it mixed with the water or with the compressed air or with 110 the water and compressed air depending upon which valves have been opened.

In the cleaning of automobiles it has been found that no matter how careful the hand-washer may be, it is practically impossible to avoid the collection of grit or dirt on his 5 sponge or brush which causes damage to the painted or enameled surface. This is eliminated when a construction as herein described is employed.

My device is also especially applicable for 10 the cleaning out of the interior of limousines which, ordinarily consumes about ten minutes of a man's time in order to dust and clean it and sweep out the dust and cigar ashes and other foreign materials which collect there.

The upholstering and top of the automobile can be readily cleaned by drawing a gasoline vapor through the vacuum line.

My device can also be employed to advantage for the cleaning of an engine or any other greasy part of an automobile which often needs attention and it has also been found to be very useful in placing upon steel parts a thin coating of very hot grease 25 in order to keep such parts from rusting, it being understood that the vacuum valve can be adjusted to provide any different mixture desired.

Under present operating conditions around 30 a garage, it is necessary to have both air and water, the air being essential for the inflating of the tires, the operation of the air drills, hammers, burners, blacksmith forge and other devices and in railroad yards and shops 35 equipped with compressed air to utilize the operation of switches, signals and other devices, so that my invention is readily adapted to be employed for the cleaning of railroad coaches, Pullman cars, trolley cars and similar uses.

In the washing of a vehicle, such as for 40 example, an automobile, the exterior of the machine will be first coated with a soapy solution which will be drawn into the discharge nozzle 1 through the vacuum pipe 7, after 45 which it can be washed off by water passing through the pipe 1 and then the wood-work of the machine can be readily and quickly dried by utilizing simply compressed air 50 passing through the nozzle 1.

It will now be apparent that I have devised a new and useful cleaning device which embodies the features of advantage enumerated

as desirable in the statement of the invention and the above description, and while I 55 have, in the present instance, shown and described a preferred embodiment thereof which will give in practice satisfactory and reliable results, it is to be understood that such embodiment is susceptible of modification in various particulars without departing from the spirit or scope of the invention or sacrificing any of its advantages.

Having thus described my invention, what I claim as new and desire to secure by Letters Patent, is:

1. In a cleaning device adapted to be manually supported and manipulated, a sectional water pipe of substantially uniform bore throughout its length and having one end 70 forming a discharge end of the cleaning device and its other end in communication with a source of water supply, a fitting connecting said sections, a vacuum pipe in valve controlled communication with said fitting, a valve controlled compressed air pipe spaced from said water pipe and at its forward end extending into said pipe to discharge on the outlet side of said fitting, and a valve controlling said water pipe.

2. In a cleaning device adapted to be manually supported, a longitudinally extending water pipe having its forward end forming the discharge nozzle of the cleaning device and its rear end in communication with a source of water supply, a valve for said water pipe, a compressed air pipe having its rear end in communication with a source of compressed air and having its forward end telescoping into the discharge end of the water pipe, said compressed air pipe being spaced from said water pipe and forming with the water pipe handles whereby the nozzle is manipulated, spring clips connected with the compressed air pipe and with the water pipe to maintain them in spaced relationship, a valve for the compressed air pipe, a valve controlled fitting communicating with the water pipe between the valve of the latter and the discharge end of the compressed air 100 pipe, and a pipe communicating with said fitting.

SIDNEY L. SELLARS.
